US00D987953S

(12) **United States Design Patent** (10) **Patent No.:** **US D987,953 S**
(45) **Date of Patent:** **** Jun. 6, 2023**

(54) **FOOTWEAR**

(71) Applicant: **Target Brands, Inc.**, Minneapolis, MN (US)

(72) Inventor: **Masha Kroshinskaya**, Minneapolis, MN (US)

(73) Assignee: **Target Brands, Inc.**, Minneapolis, MN (US)

(**) Term: **15 Years**

(21) Appl. No.: **29/832,666**

(22) Filed: **Mar. 29, 2022**

CLAIM

The ornamental design for a footwear, as shown and described.

DESCRIPTION

FIG. 1 is front, top and right side perspective view of a footwear according to the new design;

FIG. 2 is a back, bottom and right side perspective view of the embodiment of FIG. 1;

FIG. 3 is a front elevation view of the embodiment of FIG. 1;

FIG. 4 is a back elevation view of the embodiment of FIG. 1;

FIG. 5 is a right side elevation view of the embodiment of FIG. 1;

FIG. 6 is a left side elevation view of the embodiment of FIG. 1;

FIG. 7 is a top plan view of the embodiment of FIG. 1; and, FIG. 8 is a bottom plan view of the embodiment of FIG. 1. The broken lines in the drawings show portions that form no part of the claimed design.

1 Claim, 7 Drawing Sheets
